UNITED STATES PATENT OFFICE.

PHILIP JOHN WALSH, OF SAN FRANCISCO, CALIFORNIA.

REPEATER.

Application filed February 23, 1926. Serial No. 39,974.

This invention relates to a device for re-laying signals, such as telephone or telegraph signals.

When messages are sent over a wire for 5 long distances, the signals become unavoidably attenuated, due primarily to impedance losses and leakage losses. For that reason, it has been customary to supply relays or repeaters in series in the line, to amplify the signaling impulses. Such repeaters are required to work in either direction; so that, weak impulses coming from either 10 end of the line are amplified and relayed to the other end. In prior schemes, such relay-ing or repeating is accomplished only with the aid of delicate and expensive apparatus, for the amplification must be accomplished without distortion; this is especially important in telephone work. Furthermore, 15 with many such repeaters, it is difficult to install them in existing lines.

It is one of the objects of my invention to overcome all these disadvantages, and to provide a simple and efficient repeater that 20 operates without distortion.

It is still another object of my invention to make it possible to amplify the signaling impulses in such manner that the identity of the impulses are never lost; but, instead, 25 an augmentation or building up process is utilized for superimposing upon the weak signal, impulses that are exactly in phase with those to be amplified.

It is still another object of my invention 30 to make it possible to amplify the original impulses greatly, so that fewer repeaters need be used in a given length of line. In this connection, my invention operates to "pick up" signals that are very weak, and 35 this too helps to reduce the number of required repeaters.

My invention possesses many other advantages, and has other objects which may be made more easily apparent from a consideration of one embodiment of my invention. For this purpose I have shown a form 40 in the drawings accompanying and forming part of the present specification. I shall now proceed to describe this form in detail, 45 which illustrates the general principles of my invention; but it is to be understood that this detailed description is not to be taken in a limiting sense, since the scope of my invention is best defined by the appended 50 claims.

Referring to the drawings:

The single figure is a wiring diagram of one form of my invention shown installed in a line, such as a telephone circuit.

In this figure, the lines 1 and 2 are shown 60 as of indefinite length, connecting the two subscribers' stations 3 and 4. The repeater arrangement can be installed in a short section of the line—about two feet or thereabouts—and acts to augment a weak signal 65 flowing from either direction by inducing, as in a coil 23 in series in the line 1, electrical energy in phase with the impulses to be amplified. The coil 6 in line 2 is used merely to render the entire arrangement 70 symmetrical.

In order to pass energy at the right phase to coil 23, use is made of an amplifier system that is operated in accordance with the signaling impulses. As one form of such an 75 amplifier system, there is shown a scheme heretofore described and claimed in an application filed Feb. 24, 1925 in my name, having Serial No. 11,371, and entitled, "Amplifier system." This includes a thermionic 80 amplifier device 7, having a double set of electrodes, therefore being the equivalent of a pair of single devices, which could in fact be substituted for that shown. The amplifier has a filament 8, heated by the passage 85 of a regulated amount of current from a source 9, such as a battery. On either side of the filament 8 there is a plate 10 or 11, to which the electrons given off from the filament 8 are attracted.

The currents flowing between plates 11 and 10 to the filament 8 are furnished from a common source 12, which is so arranged that it supplies substantially a constant direct current, as by having one or more heavy 95 impedance coils 13, 14 in series therewith. The circuit for these space currents can be traced as follows: from the positive terminal of battery 12, coil 13, tap 15 on a resistance 16, where the current divides; a 100 part goes through the left hand portion of this resistance, coil 17, plate 11, to filament 8; and the other part goes through the right hand portion of resistance 16, coil 18, plate 10, to filament 8, where the currents recombine, and flow through coil 14 to the negative side of battery 12. 105

The coils 17 and 18 are differentially arranged on a leg 19 of a core 20, and the tap 15 is adjusted to such a position that the 110

coils exactly neutralize each other while no impulses pass between the stations. Control electrodes 21 and 22 are interposed in the space current paths to vary the impedances thereof in a well-understood manner. These electrodes are controlled in accordance with the impulses in lines 1 and 2, to produce a large unbalance of magnetism in core 20, and thereby to induce a current in the coil 23 that is placed on core 20. Let us assume for example that there is imparted to electrode 21 a negative potential with respect to filament 8; then the space current between this filament and plate 10 is reduced. Since in this instance constant current is supplied to both space current paths, this reduction causes a corresponding increase of current in the coil 17. The coils 17 and 18 being opposed, this means an increasing flux in one direction through coil 23, setting up an E. M. F. therein which is useful in augmenting the current flow to amplify the signal passing therethrough, in a manner to be hereinafter described.

The reverse effect takes place when electrode 21 is charged positive; that is, the E. M. F. induced in coil 23 increases in the opposite direction than before; but due to the arrangement that will be described, this direction changes only when the direction of the signal impulse changes, whereby the coil 23 nevertheless augments these impulses.

The unbalance between coils 17 and 18 can easily be accentuated by the aid of the control electrode 22, which is caused to vary the impedance of the space current path between filament 8 and plate 11, in a sense opposite to that of the other space current path. For this purpose, another coil 24 is inductively associated with coils 17 and 18 so as to respond also to the unbalanced condition, and is connected between the filament 8 and electrode 22, in such manner as to influence the space current in the desired direction.

To control the building up process of the magnetism in core 20, an adjustable armature 25 is inserted in a gap between the coils 18 and 24.

The initiation of the actions in tube 7 is controlled by grid 21, the circuit for which can be traced as follows: from filament 8, secondary coil 26 of a transformer 27, the primary 28 of which is in series in one of the lines, such as 1, secondary coil 29, of which coil 5 paralleling coil 23, is the primary, to grid 21. It is evident that the combined potentials of coils 26 and 29 are used to influence grid 21, and the arrangement is such that this combined potential is always the exact equivalent of the impulse being transmitted. For this purpose, coils 5, 23, and 29 are so proportioned that the E. M. F. across coil 29 is exactly the same as that across coil 23. Also, coils 23 and 5 are made with the same number of turns and of ex-

actly the same impedance. Coils 29 and 28 are in bucking relation as regards their E. M. F.'s.

The operation of the system can now be more thoroughly described. While no impulses are being sent through lines 1 and 2, the battery 12 merely supplies equal and opposite currents to coils 17 and 18, since the control electrodes 21 and 22 are inactive, and the space current paths accordingly having equal impedances. Now let us assume that an impulse begins, say in a direction indicated by arrow 30, and is originated at station 3. At first, the current divides at point 31, half going through coil 23, and the other half through coil 5. It recombines, and flows through primary 28, to subscriber #2.

An E. M. F. is induced in coil 29 of such direction as will make, let us say, the right hand terminal positive, and an E. M. F. is also induced in coil 26 that will make its right hand terminal negative. The E. M. F.'s at this instant in coils 29 and 26 are cumulative, and serve to impress a positive potential difference between filament 8 and grid 21. This causes an instant increase in current through coil 18, and a corresponding decrease through coil 17; the coil 24 acts to reinforce this difference. A magnetic field is thus being set up in core 20 through the legs upon which coils 23, 17, and 18 are wound, in a clockwise direction. The coil 23 is connected in such manner that an E. M. F. is thereby induced in it in a direction represented by arrows 30. It is evident that this E. M. F. serves to send a current through coil 23 that assists the current from station 3, and is in a direction opposing the current that would flow in coil 5 due to the signal directly. In other words, the current through coil 5 is reversed, and in a direction represented by dotted arrows 32, since now coil 23 is a source of current, instead of an impedance.

It is thus evident that as a consequence, the E. M. F. in coil 29 is reversed, and now bucks that of the coil 26. This E. M. F. is an exact measure of the boosting E. M. F. of coil 23, as specified heretofore; therefore the resultant E. M. F. which is impressed between grid 21 and filament 8 is exactly equal to that of the original impulse. This can be readily appreciated from the fact that coil 26 responds to the reinforced signal, while coil 29 responds to the reinforcement, and therefore the difference in response is that which would exist if the signal impulse alone were used. In this way, it is certain that the building up process produced by the audion arrangement is kept under proper control and is never permitted to cause instability. Furthermore, variations in the line impedance can have no appreciable effect upon the operation of this repeating action,

since coils 29 and 26 automatically subtract these variations.

An impulse starting in the opposite direction, as indicated by dotted arrows 33, causes a reversal in the actions, such that the coil 23 becomes a source of potential which is nevertheless in phase with this impulse. Thus the left hand terminal of coil 29 is momentarily positive; and the left hand terminal of coil 10 26 is negative; grid 21 acquires a negative charge, causing the coil 17 to overpower coil 18, and an increasing magnetic flux exists through coil 23 in an opposite direction than before. Therefore the phases are again correct. 15

It is also readily seen that the coil 23 virtually acts as a boosting E. M. F. in series with the line, and that this takes place irrespective of the reversal of the line E. M. F. 20 Therefore it is immaterial, so far as the repeater is concerned, where the impulse originates, whether at subscriber #1 or subscriber #2. It can readily be installed in a single line; the coil 6 acting to insert in the 25 other line, a balancing impedance, whereby conditions remain balanced.

I claim:

1. In a system of the character described, a circuit through which impulses may be transmitted in either direction, an amplifier having an output circuit in series in the circuit, and means for affecting said amplifier so as to cause it to transmit a boosting electromotive force to the circuit for either direction of transmission, comprising means operated in accordance with the difference between the augmented impulse and the effect of the amplifier in the system. 35

2. In a system of the character described, a circuit through which impulses may be transmitted in either direction, an amplifier having an output circuit in series in the circuit, and means for affecting said amplifier so as to cause it to transmit a boosting 40 electromotive force to the circuit, comprising a coil connected in the system in such a manner that an electromotive force exists across it that is an exact measure of the electromotive force of the amplifier output 45 both in direction and amount, and a coil having an electromotive force which is a 50

measure of the augmented impulse, said two coils being connected in opposing series relation.

3. In a system of the character described, 55 a circuit through which impulses may be transmitted in either direction, a transformer having a primary coil in series with said circuit, another transformer having its primary in series with said circuit, both of said 60 transformers having secondary coils, the secondary coils being connected in series opposed relation, an amplifier operated in accordance with the combined electromotive force of the said secondary coils, and means 65 whereby the output electromotive force of the amplifier is impressed in the circuit in parallel with the primary coil of the first mentioned transformer.

4. The system as claimed in claim 3, in 70 which the secondary coil of the first mentioned transformer has such number of turns that it has an electromotive force across it that is always equal to the electromotive force of the amplifier output. 75

5. The system as claimed in claim 3, in which the amplifier comprises means forming a pair of space current paths for electronic emission, and a source of constant direct current for said paths, the combined 80 electromotive force of the two secondary coils acting to vary the relative impedances of the paths, and the variations in said impedances acting to influence the output electromotive force. 85

6. The system as claimed in claim 3, in which the secondary coil of the first mentioned transformer has such number of turns that it has electromotive force across it that is always equal to the electromotive force of the amplifier output, and in which the amplifier comprises means forming a pair of space current paths for electronic emission, and a source of constant direct current for said paths, the combined electromotive force 90 of the two secondary coils acting to vary the relative impedances of the paths, and the variations in said impedances acting to influence the output electromotive force. 95

In testimony whereof I have hereunto set 100 my hand.

PHILIP JOHN WALSH.
